Primary Examiner — Elizabeth J Oswecki(74) *Attorney, Agent, or Firm* — David W. Carstens; Carstens & Cahoon, LLP**CLAIM**

The ornamental design for a Christmas cross, as shown and described.

DESCRIPTION

FIG. 1 is a perspective view of a Christmas cross showing my new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken lines shown in the drawings represent portions of the Christmas cross that form no part of the claimed design. All surfaces not shown form no part of the claimed design. All sides not shown form no part of the claimed design.
